[57] **CLAIM**

The ornamental design for a forte grip for bows of stringed instruments or the like, substantially as shown and described.

DESCRIPTION

FIG. 1 is a perspective view of a forte grip for bows of stringed instruments or the like showing my new design. The broken line showing of a bow portion is to show environment only.

FIG. 2 is a front elevation thereof, the rear being a substantial mirror image;

FIG. 3 is a top plan view thereof;

FIG. 4 is a sectional view taken along the line 4—4 in FIG. 2;

FIG. 5 is a bottom plan view; and

FIG. 6 is a side elevation thereof, the opposite side being a substantial mirror image.

FIG. 1

FIG. 6

FIG. 2

FIG. 3

FIG. 5

FIG. 4
